CLAIM

The ornamental design for a container for a confectionery, as shown and described.

DESCRIPTION

FIG. 1 is a front right perspective view of a first embodiment of a container for a confectionary showing our new design; FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front right perspective view of the container for a confectionary of FIG. 1, showing a portion of the lid portion thereof in an alternate position;

FIG. 9 is a front right perspective view of a second embodiment of a container for a confectionary showing our new design;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof; and,

FIG. 16 is a front right perspective view of the container for a confectionary of FIG. 9, showing a portion of the lid portion thereof in an alternate position.

The broken lines appearing in FIGS. 1-16 represent environmental subject matter only and form no part of the claimed design.

1 Claim, 8 Drawing Sheets
